CLAIM

The ornamental design for an arm rest, as shown and described.

DESCRIPTION

FIG. 1 is a perspective view of a first embodiment of an arm rest showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a view similar to FIG. 4 of another embodiment of an arm rest in accordance with the present invention;

FIG. 9 is a bottom plan view thereof; and,

FIG. 10 is a front elevation view thereof.

The right side elevational view of the embodiment of FIG. 8 is substantially similar to the right side elevational view shown in FIG. 2. The left side elevational view of the embodiment of FIG. 8 is substantially similar to the left side elevational view shown in FIG. 3. The rear elevational view of the embodiment of FIG. 8 is substantially to the rear elevational view shown in FIG. 7.

The fragmented mesh-like pattern shown on the surfaces is understood to be continuous throughout.

The broken lines shown in FIG. 3 represent stitching.

FIGS. 2 through 10 have been shown on an enlarged scale.
